CLAIM

The ornamental design for a handle for electrosurgical instrument, as shown and described.

DESCRIPTION

FIG. 1 is a top perspective view of a handle for electrosurgical instrument;

FIG. 2 is a top plan view thereof;

FIG. 3 is a left side elevation view thereof;

FIG. 4 is a bottom plan view thereof;

FIG. 5 is a right side elevation view thereof;

FIG. 6 is a proximal elevation view thereof, and,

FIG. 7 is an distal elevation view thereof.

The broken lines shown in the drawings are included for the purpose of illustrating structural environment and form no part of the claimed design.
